CHAIR AND SOFA HINGE

Virgil P. Carrick, High Point, N. C.

Application September 2, 1948, Serial No. 77,474

4 Claims. (Cl. 5—57)

1

This invention relates to an adjustable and releasable hinge to be used particularly in association with a chair or sofa bed.

The primary object of this invention is to provide a novel hinge for attachment to the seat and back members of a chair or sofa bed whereby the back member may be elevated from a prone position to adjusted, inclined positions.

Another object of this invention is to provide a hinge of the character described including an automatic release which is set into operation simply and effectively at a predetermined elevated position of the back member with respect to the seat member.

Yet another object of this invention is to provide a hinge of the character described wherein the release mechanism functions to block the re-engagement of a locking pin in locking teeth throughout the entire downward movement of the back member with respect to the seat member from its highest elevated position to its lowest or prone position.

A further object of this invention is to provide an adjustable releasable hinge comprising a first member having a plurality of locking teeth, a second member pivoted to the first member, a link pivoted to the second member, a locking member carried at the free end of the link, means urging the locking member into engagement with the locking teeth, means carried by the teeth for forcing the locking member out of engagement with the locking teeth, and a novel release means for blocking reengagement of the locking member and the locking teeth at a predetermined elevated position of the first member upon the second member.

These, together with various ancillary objects and features of the invention which will later become apparent as the following description proceeds, are attained by the device, a preferred embodiment of which has been illustrated, by way of example only, in the accompanying drawings, wherein:

Figure 1 is a side elevational view of the hinge of the instant invention shown attached to a seat member, a back member and the frame of a chair or sofa bed;

Figure 2 is a top plan view of the hinge as shown in Figure 1;

Figure 3 is a longitudinal sectional view taken substantially on the plane of section line 3—3 of Figure 2;

Figure 4 is a reduced sectional view similar to that shown in Figure 3 demonstrating the prone position of a sofa bed or chair;

2

Figures 5 to 8 are schematic showings of the different positions of inclination of the sofa bed or chair, and

Figure 9 is a fragmentary elevational view of a detail of construction.

Specific reference will now be made to the drawings. In the several views, in the accompanying drawings and in the following specification, similar reference characters indicate corresponding elements throughout.

Indicated generally at 10 is the frame member of a chair or sofa bed having side members 12 and 14. Secured to the side members 12 and 14 by means of suitable bolts 16 are a pair of brackets 18 which are substantially L-shaped longitudinally extending members. The seat member 20 and back member 22 are pivotally adjusted upon the bottom frame member 12 by means of the novel hinge 24 of the instant invention.

Secured to the seat member 20 at the rear end thereof by means of appropriate screws 26 and nuts 28 are a pair of L-shaped plates having a vertical, slightly rearwardly inclined member 30 and a base member 32. Secured to the front portion of the back member 22 by means of suitable screws 34 and nuts 36 are similar L-shaped members having upstanding side portions 38 and base portions 40.

Pivoted to each of the side brackets 18 by means of a suitable pivot pin 42 is a link 44, which link at its other end is pivoted to the plate 30 by means of a suitable pivot pin 46. It should be noted at this point that the link 44 is pivoted to the bracket 18 adjacent its forward end while another link of similar shape and design 48 is pivoted by means of a pivot pin 50 to the bracket 18 at its rear end. The links differ in length, preferably 1 1/4 inches, for centering prone positions. At the upper end of the link 44 a further pivot pin 52 is provided which extends through the vertical plate 30 attached to the seat member 20 and the plate 38 attached to the back member 22, as clearly shown in Figure 2.

Rotatably secured to each pivot pin 46 at its inner end adjacent the inner surface of the vertical plate 30 is a latch bar 54 which is further provided at its free end with a horizontal lug 56 that extends beyond both the inner and outer faces of the latch bar 54 itself. The lug further extends through and is guidably received in a slot 57 in the plate 30. As will be seen later, this lug 56 is, in effect, a locking member. As will be seen more clearly in Figures 3 and 4, each of the plates 30 is further provided with an aperture 58 for receiving one end of a spring 60 which is

wound around the pivot pin 46 and is hooked at its free end 62. This spring 60 urges the lug 56 into engagement with locking teeth on the plate 38, which will be described hereinafter.

The bottom edge of each of the plates 38 secured to the back member 22 is provided with a plurality of teeth 64 which are arcuate to produce cam surfaces, as at 66. The forward edge of the plate 38 immediately in front of the forwardmost tooth is also arcuate to produce a cam surface 68.

Freely rotatable on or pivoted to the inner end of each of the pivot pins 52 is a release member 70 which is preferably sectoral in shape having an outer cam surface 72. Above the pivot pin 52, each plate 38 is provided with an inwardly extending lug or stop 74 for limiting the rotation of the release member 70, and the plate 38 is further provided with another internally extending lug 76 which is positioned slightly above the rearmost tooth 66. The stop 74 is so situated that when lug 56 passes the corner of cam 72, the spring will allow lug 56 to force the release member 70 downward, thus creating positive action if the release member 70 does not fall by gravity. The slot 57 for guiding and retaining the lug 56 also assists in this action.

The structural elements of the novel hinge hereinabove described will be best understood with reference to the actual operation of the hinge. Starting from the prone position shown in Figure 5, as the rear member 38 is elevated, the lug 56 is forced into engagement with the rearmost teeth 64 of the plate 38 by the spring 60. A position of inclination is obtained analogous to that shown in Figure 6. As the rear member 22 is further elevated, the cam surface 66 of the teeth 64 force the lug 56 out of engagement with the teeth, pivoting the latch bar 54 downwardly against the action of the spring 60. When the notch formed about the second tooth is reached, the spring 60 again urges the lug 56 into engagement with the second tooth, providing an inclination analogous to that shown in Figure 7. The process hereinabove described is repeated until the notch associated with the forwardmost tooth is engaged by the lug 56. When the rear member 22 is further elevated a slight distance, the cam surface 68 carried by the plates 38 will press against the inner end portion of the lug 56, disengaging it from the forwardmost notch. At this point, the release member 70 will drop down by gravity so that the cam surface 72 overrides the outer end portion of the lug 56, preventing the latter from re-engaging any of the teeth. In the event that the release member 70 does not drop by gravity, positive action for urging it downwardly is attained as follows. The stop 74 is so situated that when lug 56 passes the corner of cam 72, the stop 74 will strike the front edge of the release member 70 to supply a momentary kick thereto and force the release member 70 downwardly. As the rear member 22 is now moved in a downward direction, the stop 76 will engage the rear edge of the release member 70, as shown clearly in Figure 4, until the rear member is in a prone position, as shown in Figure 5, at which point the release member 70 will clear the lug 56, so that the above procedure for elevating the rear member in adjusted positions could be repeated. The provision of two pivot bars or links 44 and 48 will obviously permit the swivelling of both the seat member and rear member upon the base frame in different positions of inclination.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. An adjustable and releasable hinge comprising a first plate having a plurality of locking teeth in one of its edges, a second plate, a pivot pin extending through said plates securing them together for vertical pivotal movement of said first plate on said second plate, a latch bar vertically pivotal upon said second plate, a locking lug extending transversely through said latch bar adjacent its free end, said lug having inner and outer end portions, resilient means normally urging said latch bar upwardly and said inner end portion of said lug into locking engagement with said teeth, inclined cam surfaces on said teeth for urging said lug out of engagement with said teeth and against action of said resilient means upon upward movement of said first plate on said second plate, and release means for blocking re-engagement of said lug in said teeth at a predetermined upward pivoted position of said first plate on said second plate, said release means including a cam surface on said one edge of said first plate adapted to force said inner end portion of said lug downwardly and out of engagement with said teeth against action of said resilient means, and a cam member rotatably mounted for vertical movement on said pivot pin and adapted to engage said outer end portion of said lug after the latter has been disengaged from said teeth.

2. The combination of claim 1 wherein said cam member is a sector-shaped plate rotatably mounted adjacent its apex on said pivot point, the arcuate edge of said sector-shaped plate being adapted to engage said outer end portion of said lug.

3. The combination of claim 2 and a stop carried by said first plate adapted to strike one of the straight edges of said sector-shaped plate and urge the same downwardly and into engagement with said outer end portion of said lug when said first plate attains said predetermined upward pivotal position.

4. The combination of claim 3 and a second stop carried by said first plate adapted to strike the other straight edge of said sector-shaped plate and move the latter upwardly and over said outer end portion of said lug when said first plate is pivoted downwardly on said second plate.

VIRGIL P. CARRICK.
